US00D925270S

(12) **United States Design Patent** (10) Patent No.: **US D925,270 S**
(45) Date of Patent: **** Jul. 20, 2021**

(54) **BLENDER**(71) Applicant: **SHARKNINJA OPERATING LLC**,
Needham, MA (US)(72) Inventors: **Sam William Bannister**, Leybourne
(GB); **Michael Sloban, Jr.**, Cambridge,
MA (US); **Kristof Benedict Fogarasi**,
Norwood, MA (US)(73) Assignee: **SHARKNINJA OPERATING LLC**,
Needham, MA (US)(**) Term: **15 Years**(21) Appl. No.: **29/694,050**(22) Filed: **Jun. 6, 2019**(51) LOC (13) Cl. **31-00**

(52) U.S. Cl.

(57) **CLAIM**

The ornamental design for a blender, as shown and described.

DESCRIPTION

FIG. 1 is a perspective view of a blender, showing our new design;

FIG. 2 is a front view of the embodiment shown in FIG. 1;

FIG. 3 is a rear view of the embodiment shown in FIG. 1;

FIG. 4 is a side view of the embodiment shown in FIG. 1;

FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the figures are for environmental purposes only and form no part of the claimed design.
